[57] CLAIM

The ornamental design for a luminescent display terminal, as shown and described.

DESCRIPTION

FIG. 1 is a front, top and side perspective view of a luminescent display terminal, showing my new design;

FIG. 2 is a top and front perspective view thereof;

FIG. 3 is a right side perspective view thereof, the left side perspective view being a mirror image; and,

FIG. 4 is a top perspective view thereof.

With the exception of the base and electrical cord, the rear surface is flat and unornamented.
